FLANGE ROLLING MILL

Charles E. Stenson, Hubbard, and Alden W. Kelly,
Youngstown, Ohio, assignors to The Youngs-
town Steel Tank Company, Youngstown, Ohio,
a corporation of Ohio

Application January 17, 1948, Serial No. 2,834

5 Claims. (Cl. 153—29)

1

This invention relates to apparatus for flanging the marginal edges of sheet or plate metal disks such as are employed in steel tank constructions. Considerable difficulty is encountered, when using present machines and methods to flange tank end disks of heavy gauge metal, in accurately forming the flanges to uniform axial length, to uniform and proper inner and outer radii of curvature, and without the appearance of sharp corners or checks which may be the beginning of lines of fracture after the plate is welded. Steel structures, particularly tanks fabricated of steel plate, must be manufactured in strict accordance with rigid engineering specifications and among the most important of these is the observance of certain minimum radii in the curvature of the stock.

It is accordingly the primary object of this invention to provide improved apparatus for flanging metal disks and the like which is operative to effect the requisite deforming of the metal plate in a progressive yet positive manner whereby the plate will be curved about predetermined radii without checking or buckling and whereby the final dimensions of the flanges formed will lie within predetermined close tolerances. This general object is accomplished in accordance with the principles of the invention, primarily by accurately centering and guiding the disk to be flanged with respect to the flanging roll pass of the assembly and by employing for the flanging roll pass a very rigidly journaled anvil roll of precise configuration and a co-acting working roll which is mounted for both progressive axial movement about its axis of driven rotation and transverse movement of its axis of rotation whereby the metal of the peripheral portion of a disk overlying the anvil roll may be ironed down over the anvil roll by the working roll.

Another object of the invention is the provision in a flange rolling assembly having an anvil roll rotatable about a fixed axis and a co-acting working roll rotatable about a movable axis of an improved arrangement for driving both said rolls in unison.

A further object of the invention is the provision of an improved assembly for journaling a metal bending roll whereby the axis of rotation thereof may be shifted laterally and the position thereof may be moved axially along said axis of rotation even while said roll is being power-driven.

The above and other objects and advantages of the invention will become apparent upon consideration of the following detailed specification and the accompanying drawing wherein there is disclosed a preferred embodiment of the invention.

2

In the drawing:

Figure 1 is a side elevation, partly in section of an assembled apparatus constructed in accordance with our invention;

Figure 2 is a plan view of a portion of the assembled apparatus of Figure 1;

Figure 3 is a plan view of another portion of the assembled apparatus of Figure 1;

Figures 4 and 5 are front and side elevations, respectively, of a hold-down roller used in the assembly of Figure 1;

Figure 6 is an end elevation of the rolling mill portion of the assembled apparatus of Figure 1;

Figure 7 is a vertical section through the mill of Figure 6; and

Figures 8, 9 and 10 are fragmentary views showing the anvil roll and the forming roll of the assembly of Figure 1 in three different possible relative positions.

20 The assembled apparatus of our invention comprises a rolling mill stand having an anvil roll 10 and a working roll 11 and an adjustable holder for the metal discs to be flanged having a center post 12. Normally, such discs will be dished and one such pre-formed disc is shown at 13 in the drawing.

The rolling mill comprises a structure having a suitable base 14 from which extend upwardly four spaced columns 15 mounting a platform 16 on their upper ends. Slideably mounted on the columns 15 is a pair of brackets 17 and rigidly mounted in the bracket 17 in spanning relation therewith is a tube 18 having a longitudinal slot 19 in its side wall. Slideable longitudinally in

35 the tube 18 is a second tube 20 which rotatably carries a shaft 21 to one end of which is securely but detachably mounted the working roll 11. Suitable radial and thrust bearings, not shown in detail, are employed to journal the shaft 21

40 in the sleeve 20 and to move the sleeve 20 axially of the housing 18 there is provided a bracket 22 which is rigidly keyed and secured to the sleeve 20 and which extends outwardly of the housing 18 through the slot 19 therein.

45 The end of the shaft 21 opposite the roll 11 is splined in a worm wheel 23 which is journaled in a housing 24 rigidly secured to an end of the housing 18 and a worm 25 is splined on a vertically disposed shaft 26 and is adapted to mesh with the wheel 23 whereby the shaft 21 may be driven from the shaft 26. As shown more clearly in Figure 7, the shaft 26 is connected at its upper end with a bevel gear 27 which is journaled in a housing 28 carried by the platform

55 16 and at its lower end to a bevel gear 29 which is journaled in a housing 31 rigidly carried by the base 14. Gear 29 meshes with the bevel gear 30 which is keyed on a shaft 32 extending longitudinally through the base 14. The shaft 60 32 extends outwardly beyond the housing 31 to

receive a pulley 33 which is coupled to a driving motor 34 through suitable driving belts shown.

Supported on the base 14 opposite the gear housing 31 is a rugged housing 35 rigidly journaling a heavy vertically disposed shaft 36. The anvil roll 10 is detachably secured to the upper projecting end of the shaft 36. Keyed on the shaft 36 is a worm wheel 37 which meshes with a worm 38 keyed on an extension 39 of the shaft 32. It should now be obvious that upon energization of the driving motor 34 both the rolls 10 and 11 will be positively driven and, further, that the sleeve 20 may be moved longitudinally in either direction to move the working roll 11 axially while this roll is being driven by means of the splined interconnection between the shaft 21 and the worm wheel 23. Also, the housing 18 carrying the sleeve 20 may be raised and lowered during operation of the mill by reason of the splined interconnection between the shaft 26 and the worm wheel 25. The means to raise and lower the housing 18 will now be described.

As shown in Figure 1, the ends of the housing 18 are rigidly carried in the brackets 17 which in turn are slideably mounted on the columns 15 as shown more clearly in Figure 6. Extending upwardly from each of the brackets 17 and secured thereto is a screw 40 onto which is threaded a worm wheel 41. The worm wheels 41 are positioned above the platform 16 and are engaged by a pair of worms mounted on a common shaft 42. To supply power to the shaft 42 a drive shaft 43 is provided which is connected with the upper end of the drive shaft 26 by means of bevel gears 44 and 27. A sprocket 45 is keyed onto the shaft 43 and is connected by means of a chain with the sprocket wheel 46 journaled on the shaft 42. Also journaled on the shaft 42 in spaced relation with the sprocket 46 is a worm wheel 47 which is driven by the shaft 43 through the bevel gears 48 and the worm 49. The driving arrangement is such that the wheel 47 and sprocket 46 rotate in opposite directions and each of these parts have an inner clutch face adapted to be selectively engaged by a clutch member 50 which is splined onto the shaft 42 and which is arranged to be shifted to one direction or the other, or to neutral position, by the lever 51. It will be obvious that the wheel 47 is driven at a much lower rate of speed than is the sprocket 46 and the direction of the gearing is such that when the clutch part 50 is shifted to engage the clutch face on the wheel 47 the worm wheels 41 will be rotated in the direction required to lower the housing 18. Upon the lever 51 being shifted to cause interengagement of the clutch part 50 and sprocket 46 the housing 18 will be raised.

To advance and retract the sleeve 20 in longitudinal directions a screw 52 is connected with the lower end of the bracket 22 and engaging the screw 52 is a worm wheel 53 coupled with a worm 54 arranged to be driven by a hand wheel 55. As indicated in Figure 2, the wheel 55 and lever 51 are positioned adjacent each other so that the operator through the use of both his hands may readily effect any desired combinations of movement of the working roll 11 during operation of the mill. For example, at the start of a flanging operation the roll 11 may be positioned above the roll 10 and the work may first be engaged at a point opposite the upper outer corner of the roll 10. Now by suitable manipulation of the controls 51 and 55 the outer working face of the roll 11 may be caused

to move progressively in an arcuate manner outwardly and downwardly along the contour of the roll 10. In this manner the stock is progressively formed or bent and the rate of bending may, of course, be accurately controlled in consideration of the characteristics and thickness of the metal plate stock to avoid the setting up of fracturing stresses in the stock. Also, the planishing action effected by the rolls in this mode of operation inhibits the formation of checks in the surfaces of the plate stock as will be understood.

Extending outwardly of the base 14 in general continuation of the plane of the axes of the shafts 21 and 36 is a base 56 slideably mounting a boom 57 for movement toward and away from the anvil roll 10. To advance and retard the boom 57 we provide a longitudinally extending screw 58 which, through suitable bevel gears 59 is arranged to be rotated by a hand wheel 60. Adjustably mounted on the boom 57 is a bracket 61 carrying the post 12 which has a shouldered upper end 62 for engaging an aperture formed in the exact center of the disc 13 to be flanged. It should be understood that the rolls 10 and 11 have such relative directions of rotation that their adjacent peripheral portions move in the same circumferential direction relative to the axis of post 12 whereby the disc 15 will be slowly rotated about the axis of the post 12 during operation of the mill. The post 12 is preferably of a telescopic nature whereby its height may be readily adjusted and this, together with the adjustable nature of the mounting for the boom 57 enables discs of widely varying diameters and curvature to be flanged by the machine of our invention. Further, the general dished curvature of the disc remains undistorted during the flanging operation so that the completed product is necessarily accurate to size and shape when removed from the machine.

To insure that the general curvature of the disc 13 will not be distorted during the flanging operation we provide a plurality of universally mounted hold-down rolls for spacing circumferentially about the disc 13 inwardly of its periphery. Each of such hold-down rolls 63 is journaled in a cradle 64 (see Figures 4 and 5) which is swivelled in a yoke 65 carried at the bottom end of a pin 66. Two of such assemblies are carried by the outer ends of arms 67 which are mounted on vertically disposed shafts 68 journaled in housing 69 mounted on the base 14. A worm wheel is keyed to each of the shafts 68 and is driven by a worm mounted on a common shaft 70 to which is connected an operating hand wheel 71. Upon rotation of the wheel 71 in one direction the arms 67 swing inwardly toward each other while upon rotation of the wheel 71 in the opposite direction the arms 67 swing outwardly to more widely space the hold-down points as is desirable in the case of large-diameter discs, for example. The pins 66 are preferably threaded and are secured to the arms 67 by a pair of nuts 65 engaging the top and bottom side of each of the arms 67 whereby the vertical position of the hold-down rolls may be adjusted.

Two other of the hold-down roll assemblies comprised of the roll 63 and the mounting pin 66 are carried by a bracket 72 which is adjustably mounted on the outer end of the boom 57 and which has a pair of diverging arms 73 for carrying the hold-down roll assembly. The position of the bracket 72 on the boom 57 may be finally adjusted by means of a screw 73' adapted

to be rotated by a hand wheel 74 through suitable gearing contained in a housing 75. It should be understood that upon the positioning of the disc 13 on the post 12 the arms 67 may be swung inwardly toward each other and the bracket 73 advanced toward the post 12 only sufficiently to snugly engage the upper convex surface of the disc 13 to be flanged. With proper adjustment of the height and position of the post 12 the disc 13 will at this time lie in a horizontal plane with the peripheral edge portion in light contact with the anvil roll 10 and projecting radially outward of such point of contact a sufficient distance to give the proper axial length of flange desired. Now upon application of the working roll 11 (assuming the drive motor 34 to be energized) to the work in the manner described above buckling and distortion and upward tilting movement of the disc 13 will be effectively prevented by the engagement of the hold-down rolls 63 at the four widely spaced points indicated. Of course, the pins 66 are so oriented in the holders 67 and 73 that the rolls 63 have proper rolling contact with the upper surface of the disc 13.

It should now be apparent that we have provided improved apparatus for flanging sheet and plate metal discs which accomplishes the objects initially set out. Through the use of apparatus which enables the peripheral edge portion of the metal to be deformed and ironed or planished in a progressive manner and accurately to predetermined contour formed on an anvil roll together with equipment to accurately position and restrain the rotating disc during the flanging operation we are enabled to produce accurately formed and high quality tank ends and the like from sheet or plate metal discs on a production basis. Further, these advantages are retained even though the discs handled are quite large in diameter and are very heavy plate.

The above specifically described embodiment of the invention should be considered as illustrative only as obviously many changes may be made therein without departing from the spirit or scope of the invention. Reference should therefore be had to the appended claims in determining the scope of the invention.

We claim:

1. Apparatus for flanging metal disks comprising in combination a base, upwardly disposed members forming guide-ways extending from said base, a housing slideably mounted on said guide-ways, a horizontally disposed sleeve slideably mounted in said housing for movement along its longitudinal axis, means to move said sleeve longitudinally, a shaft journaled in said sleeve and having a projecting end, a roll secured to the projecting end of said shaft, a worm wheel rotatably carried by said housing and splined onto the opposite end of said shaft, a vertically disposed driving shaft, a worm engaging said worm wheel and splined onto said driving shaft, means to raise and lower said housing, and an anvil roll journaled for rotation about a fixed axis adjacent said first-mentioned roll but angularly related to the axis of rotation of said first-mentioned roll.

2. Apparatus according to claim 1 further characterized in that said means to raise and lower said housing comprises a pair of hold-down screws connected therewith and extending upwardly therefrom, gear means threaded onto the upper end portions of said screws, and means interconnecting the upper end of said vertically disposed shaft and said gear means

to rotate said gear means in either selected direction whereby said housing may be raised or lowered.

3. Apparatus according to claim 1 further characterized in that said anvil roll is mounted on the upper end of a vertically disposed stub shaft, a housing rotatably supporting said stub shaft, a driving gear in said last mentioned housing and keyed to said stub shaft, a motor, and gear means interconnecting said motor with said drive gear and said first mentioned vertically disposed shaft whereby said rolls may be rotated in unison.

4. Apparatus for flanging metal disks comprising means for rotatably supporting a disk for rotation about its principal axis, an anvil roll for underlying a peripheral edge portion of the disk and having a working surface contoured complementary to the inner curvature desired at the flange on the disk, said anvil roll being journaled for rotation about an axis lying in a plane including said principal axis, a supporting frame adjacent said anvil roll, a horizontally disposed sleeve mounted in said supporting frame for adjustable movement either vertically or longitudinally, power means on said supporting frame for moving said sleeve vertically and having a manually engageable control member, means on said supporting frame for moving said sleeve longitudinally and having an operating member positioned adjacent said control member, the longitudinal axis of said sleeve lying substantially in said plane, a shaft journaled in said sleeve and having a free projecting end positioned adjacent said anvil roll, a working roll rigidly secured to said projecting end of said shaft and having a bulbous outer working surface, and means to drive said rolls, the arrangement being such that during a disk flanging operation said members may be manipulated to cause said working roll to move through an arcuate path over the contour of said anvil roll to thereby progressively bend said peripheral portion of said disk into close engagement with the contour of said anvil roll.

5. In a machine for flanging metal disks, apparatus for rotatably supporting said disks in generally horizontal position comprising a horizontally extending boom, a vertically disposed post mounted on one end of said boom and having a shouldered upper end to engage apertures formed centrally in the disks, and a hold-down roll carried by the other end of said boom and adapted to engage the top surface of the disk, said post being adjustable as to height, and further including means to move said hold-down roll toward and away from said post and to raise and lower the position of said hold-down roll whereby disks of varying diameter and curvatures may be rotatably mounted.

CHARLES E. STENSON.
